AWNNG SHUTTER

Lloyd M. Jones, Fort Lauderdale, Fla.

Application April 14, 1938, Serial No. 202,044

3 Claims. (Cl. 189—55)

This invention relates to what is commonly termed awning shutters and its object is to provide certain improvements in devices of that kind which render the same more serviceable, more easily manipulated, and more effective than prior devices. In general, my invention includes an awning shutter made up of a plurality of sections hinged together and pivotally supported at its upper end adjacent the upper end of a window or other opening, and which can be easily and quickly swung inwardly to close or cover and protect the window or permit it to automatically swing outwardly in position to form an awning for the window, in which latter position the parts are arranged to afford the maximum amount of light and ventilation. The invention also includes certain detailed improvements for manipulating the slats or louvers in the shutter so as to regulate the amount of sunlight and air through the window. The foregoing and other improvements in my construction will be readily understood from the accompanying drawings taken in connection with the following specification, and in which drawings:

Figure 1 is a front outside view of an awning shutter involving my invention, the shutter being in closed position and a part thereof being shown cut away;

Figure 2 is a transverse section substantially on the line 2—2 of Figure 1;

Figure 3 is a longitudinal section substantially on the line 3—3 of Figure 1;

Figure 4 is a side view of the shutter swung outwardly into open position;

Figure 5 is a detailed section on an enlarged scale showing a form of joint used between the main portion of the shutter and the lower sections hinged thereto;

Figure 6 is an enlarged edge view, partly in section, showing the hinge between the two lower hinged sections of the shutter;

Figure 6a is a section showing an alternative arrangement of hinge connection between the lower sections of the shutter;

Figure 7 is an enlarged detailed view, partly in section, showing the means for pivotally connecting the lower end of the lower section of the shutter to the thrust arm which cooperates therewith; and

Figure 8 is an enlarged detailed view showing the means employed for operating the slats or louvers on the shutter.

Referring to the drawings in detail, my invention is shown in combination with a window of a building, such as a house or other structure in-

dicated at A, and which will hereafter be referred to by the general term building. My awning shutter preferably comprises an upper or main section 10, an intermediate section 11, and a lower section 12. The section 10 is hinged at its upper end to the building A and is adapted to swing inwardly against the building or outwardly into the position shown by Figure 4 of the drawings. The intermediate section 11 is hingedly connected at its upper edge to the lower edge of the main section 10 and is adapted to hang or depend from the section 10 in the form of a valance. The section 11 may therefore be termed a valance section. The lower section 12 is hingedly connected to the lower edge of the valance section 11. The improved shutter is preferably made of a metal having sufficient thickness to produce the desired strength and lightness necessary in such a device.

The upper or main section 10 includes two longitudinally spaced side bars or members 13, a transverse upper member 14, and a transverse lower member 15. These members are rigidly secured together in any suitable manner, as by welding or riveting to form the main framework of the upper section 10. Within this main framework I preferably secure a louver construction made up of a plurality of pivoted slats or louvers, as later described, although if desired, such louvers may be dispensed with and the upper section of the shutter may be formed of one or more plane sheets of metal rigidly secured to the side members of the shutter.

One feature of my improved construction relates to the means employed for pivotally supporting the awning shutter at the upper end thereof. For that purpose a plate or bar 16 is rigidly secured to the building A adjacent to the upper end of the window or other opening to be covered by the shutter. The plate 16 extends transversely of and entirely across the opening, and its upper portion 16a is securely fastened by suitable means such as bolts or screws 17 to the window frame or other part of the building. The plate 16 is preferably bent into the shape shown in the drawings to form a hook-shaped member; in other words, the plate is bent outwardly and then downwardly and then inwardly and then upwardly so that the lower edge 16b thereof lies below and to the rear of the main body of the plate 16. Preferably, the plate 16 is bent angularly rather than in a curved form since the angle arrangement is more easily produced and is found to afford a more satisfactory form of construction.

The upper edge 14a of the transverse member 14 is so bent as to cooperate with or hook into the bent portion of the plate 16. In other words, the upper portion of the member 14 is bent outwardly and downwardly and then inwardly to correspond with the bent portions of the plate 16. The lower edge 14b of the plate 14 is bent outwardly to some extent for a purpose later described.

10 The arrangement of the angularly bent plate 16 and angularly bent member 14 provides an effective hinge support for the awning shutter. Such a hinge support produces a water-tight joint and at the same time affords simple means by which the shutter can be detached from the building, since to remove the shutter it is only necessary to move the same laterally or transversely of the opening so that the hook-shaped portion of the member 14 will slide out of the 20 hook-shaped portion of the plate 16. By the reverse operation the shutter can easily be put back into position in front of the window or other opening.

15 The side members 13 of the shutter are each preferably formed with a rearwardly extending flange 13a which is adapted to rest against the building and form a tight joint therewith. Each of the members 13 is also preferably formed with a laterally extending flange 13b which is preferably bent outwardly at the edge thereof to produce a shallow drain or trough, as later described.

20 The lower transverse member 15 of the section 10 has the upper portion thereof bent outwardly as shown at 15a, for a purpose later explained, and the lower edge 15b thereof is bent inwardly and upwardly and outwardly to form a hook-shaped portion for hingedly receiving and supporting the valance section 11 of the shutter.

25 The upper edge of the valance section 11, as indicated at 11a, is bent outwardly and downwardly and inwardly to form a hook-shaped portion which is adapted to engage and cooperate with the hook-shaped lower edge 15b of the member 15. By this means, the section 11 is hinged to the member 15 so as to swing relative thereto and form a water-tight joint therewith. It should be noted, however, that the extent to which the valance section 11 can swing 30 inwardly relative to the upper section 10 is limited. In other words, the hinge connection between these sections will permit the section 11 to swing inwardly to the substantially vertical position shown in Figure 4 or outwardly to a 35 position substantially in the same plane as the section 10.

40 The lower section 12 is connected at its upper edge to the lower edge of the valance section 11 by hinges indicated at 11b. These hinges each comprise a hinge plate 11c secured to the section 11 adjacent its lower edges and extending downwardly and inwardly thereof, and a similar hinge plate 12a secured to the upper edge of the lower section 12 and extending upwardly and inwardly thereof. The inner portions of the hinge plates 11c and 12a are bent into cylindrical shape and cut away so as to fit together to form a hinge, a pin or wire 11d forming the pintle of such hinge.

45 The lower section 12 along its upper edge is bent outwardly and downwardly to form a flange 12b and the lower edge of the intermediate section 11 is also bent outwardly and downwardly to form a flange 11e. When the awning shutter 50 is closed and the sections 11 and 12 hang ver-

55 tically, the flanges 11e and 12b engage each other so as to form a water-tight joint between the same. Also these flanges serve to prevent the lower section 12 from swinging outwardly beyond the plane of the section 11. In the modification shown in Figure 6a, the adjacent edges 5 of the sections 11 and 12 are bent rearwardly and pivotally connected by links 18 which engage a rod 18a extending through lugs 18b secured to the section 11 and a rod 18c extending 10 through a bead formed on the section 12. In this form of construction the lower edge of the section 11 extends downwardly past the links 18 and overlies the upper part of the section 12 to form a tight joint therewith.

15 Along its lower edge the lower section 12 is bent rearwardly into the form of a bead 12c, and a rod or wire 12d extends through such bead. Adjacent each end this bead is cut away at 12e to receive the end of a thrust arm 20, the rod 20 20 12d passing through an opening in the end of each of said rods 20. By this means the thrust arms 20 are pivotally connected at their outer ends to the lower edge of the lower section 12 of the shutter. At their opposite or inner ends 25 the arms 20 are pivotally connected at 20a to the window frame or side of the building.

30 The sections 11 and 12 at each end are provided respectively with rearwardly extending flanges 11f and 12f, the inner edges of which 35 flanges are adapted to rest against the window frame or other part of the building when the shutter is closed.

35 A coiled spring 21 is arranged at each side of the shutter. Each of said springs at its upper end is secured at 21a to the inner side of the shutter and at its lower end to one of the thrust arms 20 adjacent the outer end of the latter. The springs 21 are under tension at all times so that when the shutter is free to swing outwardly, these springs will serve to swing the same into the position shown in Figure 4. To swing the shutter inwardly and close the same, flexible cables or chains 22 are secured to the section 11 at 22a and extend into the building A 45 in position to be grasped and drawn inwardly to close the shutter into the position shown in Figure 3.

40 Since the thrust arms 20 are pivoted to the lower edge of the lower section 12, it will be 50 seen that when the shutter is swung outwardly by the springs 21 to the position shown in Figure 4, the lower section 12 will be automatically swung or folded up against or adjacent to the rear side of the valance section 11. By thus 55 folding up the lower section 12, the shutter when in open position offers little obstruction to vision from the window and permits ready access of light and air to the building.

55 As previously noted, I prefer to embody in my improved shutter a pivoted louver construction to further facilitate admission of light and air to the building. To that end the side members 13 of the upper section 10 are each provided with a flange 13c extending longitudinally thereof and outwardly therefrom. A series of louvers or slats 25 extend transversely of the section 10 between the flanges 13c of the side members 13. The ends of the louvers are bent rearwardly or inwardly to form flanges 25a and these flanges 70 are pivotally connected as by rivets or pivot pins 26 to the flanges 13c. Each of the louvers along its upper edge is bent rearwardly and then outwardly to form a hook-shaped flange 25b, and along its front edge is bent outwardly and 75

rearwardly as indicated at 25c to form a second hook-shaped flange. All the louvers are connected to move in unison by bars 27, one at each side of the shutter, said bars being pivotally connected to each louver by a pivot pin or rivet indicated at 28. The louvers are so mounted on the flanges 13c that when closed the bottom flanges 25c of each louver will engage over the top flange 25b of the adjacent louver. The top flange of the uppermost louver is arranged to engage beneath the lower out-turned edge 14b of the transverse member 14 as heretofore indicated, and the bottom flange of the lowermost louvers engages over the outwardly bent flange 15a of the transverse member 15. This interengagement between the flanges on the louvers and their engagement with the upper and lower members of the section 10 produces a tight and rainproof structure. Any rain passing inwardly between the flanges 13c of the shutter and the flanges 25a of the louvers will be caught and carried downwardly by the trough-shaped flanges 13b of the side members 13.

The louvers are designed to be opened and closed when desired. To open the same, one of the upper louvers has rigidly secured to the inner surface thereof on one side of its pivot a plate 30 provided with a curved portion projecting rearwardly and downwardly. A coiled spring 31 is secured at one end to the plate 30 and this spring extends downwardly over said curved portion of the plate 30 and is secured at its other end to the side member 13. The spring 31 is under tension at all times and when free to act this spring will draw the inner ends of all the louvers downwardly due to their common connection with the bars 27, and thereby all the louvers will be opened. To simultaneously close the louvers, a bar 32 is secured to the outer surface of one of the louvers, preferably the one to which the plate 30 is connected and on the opposite side of the pivot thereof. This bar 32 extends outwardly and laterally and an operating chain or cable 33 is connected to the end thereof. This chain is passed through an opening in the side member 13 and also through an opening in the window frame or building to a convenient point from which it can be manipulated inside the building. It will be apparent that when the chain 33 is drawn inwardly or rearwardly, all the louvers 25 will be closed against the tension of the spring 31 tending to open the same. The louvers may, of course, be closed when the shutter is in the closed position of Figures 1 and 3, or the open position of Figure 4. Any suitable means, not shown, may be provided for securing the chain 33 after the louvers are closed.

As before noted, when the louvers are closed

by pulling on the chain 33, the spring 31 engages the inwardly and downwardly curved portion of the plate 30. The curvature of this plate is such that during the closing of the louvers the lever arm through which the spring 31 acts is gradually shortened, that is, there is a gradual decrease in the distance between the pivot of the louver and the point where the spring contacts with the curved portion of the plate 30. As a result, the pull on the chain 33 necessary to close the louvers decreases as the louvers are moved toward closed position.

Various changes in the details of the structure as above described may be made within the scope of the invention as set forth in the appended claims.

Having thus described the invention, what is claimed as new and desired to be secured by Letters Patent is:

1. An awning shutter comprising an upper section pivotally supported on a building, a valance section pivotally connected to the lower end of said upper section, a lower section pivotally connected to the lower edge of the valance section and movable into a position at the rear of said valance section, a thrust arm pivotally connected at its inner end to the building and at its outer end to the lower edge of said lower section, a spring for moving the outer end of said arm upwardly to thereby swing the lower end of said upper section outwardly and swing said lower section into position at the rear of said valance section and means to limit the rearward swinging movement of said valance section beyond a substantially vertical position when said upper section is swung outwardly.

2. An awning shutter comprising an upper section pivoted to a building, a valance section pivoted to the lower edge of said upper section, a lower section pivoted to the lower edge of the valance section and movable into a position at the rear of said valance section, a thrust arm pivoted at one end to the building and at the other end to the lower edge of said lower section, a coiled spring secured at one end to said upper section adjacent the upper end thereof and at the other end to said arm, said arm and spring constituting means for automatically swinging the lower edge of said upper section outwardly and simultaneously swinging said lower section into position at the rear of said valance section and means to limit the rearward swinging movement of said valance section beyond a substantially vertical position when said upper section is swung outwardly.

3. A structure as defined in claim 1 having means for limiting outward swinging motion of said lower section relative to said valance section.

LLOYD M. JONES.
